UNITED STATES PATENT OFFICE.

EMIL C. BUDOLPH, OF SPRINGVILLE, NEW YORK.

BOILER ATTACHMENT FOR LOCOMOTIVE FIRE-BOXES.

1,142,731.

Specification of Letters Patent. Patented June 8, 1915.

Application filed August 13, 1914. Serial No. 856,665.

To all whom it may concern:

Be it known that I, EMIL CAESAR BUDOLPH, a subject of the German Emperor, residing at Springville, in the county of Erie and State of New York, have invented certain new and useful Improvements in Boiler Attachments for Locomotive Fire-Boxes; and I do hereby declare the following to be a full, clear, and exact description 10 of the invention, such as will enable others skilled in the art to which it appertains to make and use the same.

This invention relates to boiler attachments, and one of the principal objects of the invention is to provide means for circulating the water from the boiler through a series of small copper pipes through the fire-box direct above the fire back to the boiler to generate steam more quickly and 20 to thus save fuel, the copper pipes leading from the one portion of a water jacket from the front wall at the lower part of the fire-box into the water jacket above the fire-door back to the boiler. These and other objects 25 may be attained by means of the construction illustrated in the accompanying drawing, in which—

Figure 1 is a longitudinal sectional view of the fire-box, (except boiler), the boiler attachment and adjacent parts. Fig. 2 is a front plan view of one of the hollow cylinders to which the pipes are connected, showing the walls of one of the water jackets in section, and with the side walls of the fire-box. Fig. 3 is a top plan view from the front elevation of the flange attaching members for the hollow cylinder, and Fig. 4 is a similar view of the flange attaching members for the lower cylinder.

Referring to the drawing, the numeral 1 designates a boiler, 2 are the fire flues extending longitudinally of the boiler and attached to the front wall 3 thereof. The fire-grate 4 in the fire-box may be of the usual 45 construction, and 5 is the fire-door.

The numeral 6 designates a water jacket which communicates with the boiler and extends over the top of the fire-box, and continues around the fire-door 5 through the 50 space 7. A depending water jacket 8 communicates with 7, 6 and the interior of the boiler.

Secured to the front wall 3 of the fire-box,

and extending nearly across to the side walls 20 thereof is a hollow cylinder 14 provided with an opening 17 and attaching flange 15 secured by studs 16 to the wall 3 of the fire-box below the flues 2 and communicating through the opening 17 with the water jacket 8 of the boiler. Secured to the upper 55 wall 9 of the fire box, and extending nearly across to the side walls 20 thereof is a similar hollow cylinder 10 provided with an opening 11 and attaching flanges 12, secured by studs 13 to the wall 9 of the fire-box 60 above the fire-door 5 and communicating through the opening 11 with the water jacket 6 of the boiler.

Connected to a series of perforations 18 in the hollow cylinder 14 and equal perforations in the hollow cylinder 10, are copper pipes 19 of comparatively small diameter, said pipes are secured by unions 21 to the cylinders 14 and 10 and readily removable when required for cleaning or for other purposes.

When the fire is started in the fire-box, the water line will be somewhat above the top of the opening 11 in the cylinder 10 and when steam begins to generate the water will circulate from the water jacket 8 through the opening 17 into the cylinder 14 and through the pipes 19 into the cylinder 10 as steam, and through the opening 11, into the water jacket 6 and will keep up a constant circulation. The pipes 19 being located immediately above the bed of fire will be quickly heated in the fire-box, and will result in generating steam much quicker than by the ordinary boiler, in which the heat is utilized 80 only in passing through the flame tubes or flues 2.

From the foregoing it will be obvious that a boiler attachment made according with this invention will be a great saver of fuel 85 and labor, and will generate steam much more quickly than by the ordinary process.

The boiler attachment may be readily connected to any boiler without material expense and alteration.

What is claimed is:—

A locomotive boiler having a fire-box, a water jacket surrounding the top, back and front portions of the fire-box, a hollow cylinder connected to the upper wall of the fire-box and communicating with the water

100

105

6 jacket above said wall, a hollow cylinder connected to the rear wall of the fire-box and communicating with the water jacket at that point, and a series of tubes extending from one cylinder to the other and communicating therewith, said pipe being inclined from one cylinder to the other.

In testimony whereof I affix my signature in presence of two witnesses.

EMIL C. RUDOLPH.
